Primary Examiner — Angela J Lee*(74) Attorney, Agent, or Firm* — Marshall A. Lerner; Marvin H. Kleinberg; Kleinberg & Lerner, LLP(57) **CLAIM**

The ornamental design for an adjustable viewing stand, as shown and described.

DESCRIPTION

FIG. 1 is a front perspective view of the adjustable viewing stand in the open position showing my new design;

FIG. 2 a front perspective view thereof adapted for holding a device;

FIG. 3 is a rear perspective view thereof;

FIG. 4 is a rear perspective view thereof in the closed position;

FIG. 5 is a front elevation view thereof in the closed position;

FIG. 6 is a rear elevation view thereof in the closed position;

FIG. 7 is a right elevation view thereof in the closed position;

FIG. 8 is a left elevation view thereof in the closed position;

FIG. 9 is a top plan view thereof in the closed position; and,

FIG. 10 is a bottom plan view in the closed position.

The broken lines are included for illustrative purposes only

and form no part of the claim.
